METHOD AND APPARATUS FOR THE RAPID
PRODUCTION OF FRIGID AIR

Robert Hoffman, San Francisco, Calif.

Application October 5, 1945, Serial No. 620,449

4 Claims. (Cl. 121—129)

1

This invention relates to a new and useful method and apparatus for the rapid production of frigid air.

The main object of the invention is to take compressed air at moderate temperatures and pressures and subject it to regulated expansion at high speed in relatively small quantities and produce reduction in temperatures as low as desired within a very short time subject to precise control and regulation.

A further object is to provide a method and device which is exceedingly simple to construct and operate and which is very much smaller in compass than the usual unit and economical to manufacture.

Still another object is to provide a method and apparatus which can be easily regulated and controlled to avail itself of various pressures of air and temperature conditions wherever used.

Another object is to provide a method and apparatus which is small, compact and available for use on trucks, trailers, busses, railroad refrigerator and dairy cars, automobiles, ships, cold rooms for perishables and the like, for the purpose of achieving the desired cooling effect.

Further and more specific objects, features, and advantages will more clearly appear from the specification hereinafter especially when taken in connection with the accompanying drawings which illustrate a preferred form which the invention may assume and which form part of the specification.

For many years the problem of cold air refrigeration, without using large units of great size and high cost, has baffled many persons expert in the art. It was for the solution of this problem that the herein described invention was developed. Its simplicity of operation, through the medium of mechanical precision of moving parts so precisely timed, permits a series of intake expansion areas to be created so rapidly in the high speed operation of an expanding air motor powered by compressed air, that frigid air is almost instantly created.

The invention briefly and generally considered comprises a method and apparatus in which compressed air at normal temperatures and moderate pressures is passed through an expansion motor powered by compressed air, which is operated by the air at relatively high speed, in relatively small quantities and passes through a series of air chambers to permit its rapid expansion with consequent rapid cooling.

More particularly the motor is a multi-cylinder one having an intake manifold chamber common

2

to all the cylinders of the motor, which chamber is smaller than the volume of the cylinders when the pistons therein are positioned to exhaust the air into separate exhaust manifold chambers.

5 These exhaust chambers permit the discharge of the air at a pressure reduced to the required level.

Preferably the motor is of the piston in sleeve type. It receives compressed air from any suitable source such as those employed on railroad cars, large interurban trucks and similar vehicles and the air is generally humid.

10 The power required in operating this motor is compressed air fed to the motor at about sixty-five pounds per square inch and at about six cubic feet per minute. The identical air that powers the unit becomes the frigid air in process and release through the exhaust of the motor. No other agents are employed. Ordinary compressed air is the only medium.

15 20 The motor generates no heat in operation, nor is it possible to freeze the motor in operation, and therefore friction is at so low a minimum, that wear of moving parts is of no importance. The actual moving distance or stroke of the pistons of the motor is five-eighths of an inch. A push fan for driving air from the area of the motor operation is used solely as a laboring agent for the motor. Any useful load on the motor shaft should accomplish the same purpose.

25 30 The production of reactivated humid air has long been a problem. In this method the moisture content normally found in compressed air is transmitted through the motor and expelled by way of the exhaust as humid air, serving not only to moisture-coat the material which is to be refrigerated but to cover the surface of them and impregnate the perishables with the necessary humid air which prevents decay.

35 40 The unit because of its compactness could easily be installed on refrigerator cars, over-the-road trucks, ships, cold rooms, etc., and will show exceptional savings both in initial costs and operational costs over a short period of time as against any present known method of cooling.

45 45 The present preferred form which the invention may assume is shown in the drawings of which,

Figure 1 is a top plan view of the cold-air motor.

Figure 2 is a right-side-elevation thereof.

Figure 3 is a rear elevation thereof.

Figure 4 is a broken elevation of the crank shaft of the motor.

50 55 Figure 5 is an end elevational view of the crank shaft per se.

Figure 6 is a vertical transverse section taken through one of the cylinders of the motor.

Figure 7 is a vertical longitudinal section through the motor.

I shall now describe the physical construction and operation of the motor leaving to other portions of the specification the explanation of the manner in which the motor is tied into this novel method of producing frigid air and whatever theoretical explanations may be deemed necessary herein.

In Figures 1, 2, and 7 is shown a four cylinder motor having cylinders 11, 12, 13, and 14 from front to rear. It is supplied with compressed air through pipe 15 having therein a control valve 16. This pipe is connected to an intake manifold chamber 17 which is common to all cylinders. The volume of this manifold with respect to the other volumetric chambers such as the cylinders, and the exhaust passages is calculated. The motor is provided with individual exhaust manifolds such as 18, one for each cylinder, to which are connected exhaust pipes 19 extending to a common exhaust union or connection element 20. The ratio of the volume of these exhaust manifolds and pipes with respect to the cylinders and the intake manifold is also a predetermined one. The motor is provided with a crank shaft 21 (Figures 4 and 6) on the forward end of which is disposed a fan 22 which is provided for the purpose of driving air from the area of the motor and affording a nominal load on the motor to hold down its speed within reasonable limits.

Each cylinder of the motor is provided with a piston 23, a piston rod 24, connected in any well known manner to a crank arm 25, and is also provided with a sliding sleeve 26 having ports 27 and 28 disposed in a predetermined position with respect to an inlet port 29 and an exhaust port 30 in the walls of the cylinder. This sleeve is moved up and down by connection to a sleeve rod 31 attached to an enveloping band 32 surrounding an eccentric disk 33 mounted on the crank shaft 21. The relative movement of the piston and the sleeve in each cylinder will permit admission of compressed air from the manifold 17 through port 34 and port 29 into the cylinder at the predetermined instant of time in the operation of each cylinder. The air in the cylinder after having expended some of its energy therein will then be exhausted through the port 28, the port 30, and the port 35 into the exhaust manifold connected to that cylinder.

The top of each cylinder is closed by a block 36 having a flange 37 resting on top of the cylinder wall. Each block is hollow, projects into the cylinder, is of less diameter than the cylinder, so as to have a space around it, and is provided with ports 38 providing access for leakage of air past the sleeve 26 through the ports 38 into a chamber 39 above the cylinders to which a bleeder 40 is connected. The block in each cylinder is held in tight contact with the cylinder wall by means of adjustable bolts 41 which are journaled in the top of the motor block 42 and press down on the bottom of the hollowed portion of the block. The inner ends of the blocks are adjacent the ports 34 and 35.

In the operation of the motor thus mechanically described, the furtherance of the novel method of producing rapidly frigid air requires that a source of compressed air at moderate temperatures and pressures be available. It is therefore especially useful on trucks carrying perishable material, on railroad refrigerator cars,

automobiles and the like where small units such as this can be connected up to a source of compressed air already available for this and other purposes.

A working unit of the above described type has been built and successfully operated. Without citing exact figures or dimensions it is desired to state that a small model unit from which the herein drawings were made is in overall dimensions about fourteen inches long, twelve inches wide, and nine inches high. It has cylinders, four in number, the diameter of the pistons being approximately 1.375 inches and with a stroke of five eighths of an inch. The compressed air was supplied from a source at about sixty-five pounds per square inch at normal temperature equal to that of the surrounding atmosphere and was supplied to the motor at about six cubic feet per minute. The fan load on the motor with air supplied at this pressure caused it to run steadily at about fourteen hundred revolutions per minute. The exhaust pressure of the air dropped at about ten pounds per square inch. With these approximate figures a temperature of the air at exhaust was about forty degrees Fahrenheit in about four minutes after starting and dropped to approximately ten degrees above zero Fahrenheit in about half an hour.

It is of course obvious that the speed of the motor may be controlled by decreasing or increasing the load on the shaft; by automatically regulating the amount of air intake; by employing lower pressures for the compressed air; or by using thermostats at the exhaust connected up to regulate the inlet of air. These different contrivances are not shown since they form no part of the invention.

By the process of this invention any enclosed space can be quickly and cheaply cooled and refrigerated with compressed air from any suitable source. The effect of the cooling is uniform and an even temperature throughout the refrigerator can be obtained because the low temperature exhaust from the motor is well circulated by the fan 22.

While the invention has been described in detail and with respect to a present preferred form thereof, it is not to be limited to such details and this form since many changes and modifications may be made in the invention without departing from the spirit and scope of the invention in its broadest aspects. Hence it is desired to cover any and all forms and modifications of the invention which may come within the language or scope of any one or more of the appended claims.

Having thus described the invention, what I claim as new and desire to secure by Letters Patent, is:

1. Apparatus for producing frigid air comprising an expansion air motor having working cylinders, each of said cylinders containing a piston, a shaft having cranks thereon connected one to each of said pistons, a sleeve valve in each of said cylinders enveloping the piston therein, said valves and said cylinders having admission and discharge ports, means for connecting said sleeve valves to said shaft, means for conducting compressed air to the admission ports, hollow blocks secured one to the head of each cylinder, the blocks projecting into the cylinders, being surrounded by spaces between them and the inside surfaces of the cylinders and having ports communicating with said spaces, another block attached to the heads of the cyl-

inders over the first-named blocks, the last-named block having a chamber therein communicating with the ports in the first-named blocks, and a conduit communicating with said chamber.

2. Apparatus for producing frigid air comprising an expansion air motor having working cylinders, each of said cylinders containing a piston, a shaft having cranks thereon connected one to each of said pistons, a sleeve valve in each of said cylinders enveloping the piston therein, said valves and said cylinders having admission and discharge ports, means for connecting said sleeve valves to said shaft, means for conducting compressed air to the admission ports, hollow blocks secured one to the head of each cylinder, the blocks projecting into the cylinders, being surrounded by spaces between them and the inside surfaces of the cylinders, and having ports communicating with said spaces, another block attached to the heads of the cylinders over the first-named blocks, the last-named block having a chamber therein communicating with the ports in the first-named blocks, and a conduit communicating with said chamber, the admission and discharge ports for the cylinders being adjacent the inner ends of the blocks.

3. Apparatus for producing frigid air comprising an expansion air motor having working cylinders, each of said cylinders containing a piston, a shaft having cranks thereon connected one to each of said pistons, a sleeve valve in each of said cylinders enveloping the piston therein, said valves and said cylinders having admission and discharge ports, means for connecting said sleeve valves to said shaft, means for conducting compressed air to the admission ports, hollow blocks secured one to the head of each cylinder, the blocks projecting into the cylinders, being surrounded by spaces between them and the inside surfaces of the cylinders, and having ports communicating with said spaces, another block attached to the heads of the cylinders over the first-named blocks, the last-named block having a chamber therein communicating with the ports in the first-named

blocks, and a conduit communicating with said chamber, said motor having an intake manifold common to all said cylinders and an exhaust manifold for each cylinder.

5 4. Apparatus for producing frigid air comprising an expansion air motor having working cylinders, each of said cylinders containing a piston, a shaft having cranks thereon connected one to each of said pistons, a sleeve valve in each of said cylinders enveloping the piston therein, said valves and said cylinders having admission and discharge ports, means for connecting said sleeve valves to said shaft, means for conducting compressed air to the admission ports, hollow blocks secured one to the head of each cylinder, the blocks projecting into the cylinders, being surrounded by spaces between them and the inside surfaces of the cylinders, and having ports communicating with said spaces, another block attached to the heads of the cylinders over the first-named blocks, the last-named block having a chamber therein communicating with the ports in the first-named blocks, and a conduit communicating with said chamber, the admission and discharge ports for the cylinders being adjacent the inner ends of the blocks, said motor having an intake manifold common to all said cylinders and an exhaust manifold for each cylinder.
